UNITED STATES PATENT OFFICE

WILLIAM M. BRUCE, OF SPRINGFIELD, OHIO

METHOD AND APPARATUS FOR RECEIVING WIRELESS SIGNALS

Application filed April 30, 1928. Serial No. 273,869.

My invention relates to methods and apparatus for receiving wireless signals or high frequency oscillations.

The object of my invention is to provide methods and means for eliminating from the circuits of a wireless receiving apparatus the so-called static or disturbing impulses or oscillations so that the desired signals can be received free from such disturbances.

In carrying out my invention I make use of the well known principle that if two currents of opposite phase or polarity, but having the same frequency and characteristics are impressed upon the same circuit they will cancel or neutralize each other and of the further principle that by the aid of properly constructed apparatus as is usually included under the term filter a single definite frequency can be stopped and other frequencies will pass through the circuit.

In its simplest form I employ in an ordinary wireless receiving apparatus a local circuit including a filter preferably having variable tuning and I connect this local circuit to the regular receiving circuit in such a way that the local receiving circuit has impressed upon it all of the incoming oscillations and impulses in the usual manner. By the aid of the filter or equivalent devices I prevent the passage through this auxiliary circuit of the frequency which it is desired to receive in the receiving set. The other frequencies are allowed to pass through to the local circuit and are then impressed upon the circuit of the regular receiving apparatus in such a manner that all impulses or oscillations having like frequencies or characteristics are cancelled. Thus the "tuned in" incoming frequency is the only one which will pass through the regular receiving circuit free from the static or other disturbing influences which have been concealed by like frequencies or disturbances of opposite phase impressed thereon.

In the accompanying drawings which are diagrams of various circuits and modifications embodying my invention:

Fig. 1 shows a well known type of super-heterodyne circuit to which my invention has been applied.

Fig. 2 shows my invention applied to a

simple receiving circuit of well known form having a single amplifying tube.

Fig. 3 is a similar circuit in which a special form of tube with multiple grids is shown.

Fig. 4 is a view of a similar circuit with slight modification in the wiring connections.

Fig. 5 is a diagram of a well known circuit having two radio amplifying tubes and a local cancelling circuit, which also has there-in an amplifying tube.

Fig. 6 is a similar view with slight modifications.

Fig. 7 is a diagram showing the application of my invention to a receiving circuit such as is used in the reception of wireless telegraphy or undamped oscillations with a local heterodyne.

Figs. 8 and 9 are views showing modifications and including amplifying tubes in the auxiliary circuit.

Fig. 10 is a detail view showing a special form of filter.

Figs. 11 and 12 are modifications in which an amplifier and oscillator are used in the auxiliary or cancelling circuit.

Referring to Fig. 2 in which a circuit of simple form is shown 1 represents an ordinary radio amplifying tube. The aerial A is connected by transformer T, with the usual variable condenser, to the grid of the tube and the plate circuit of the tube is connected through transformer T' to the next succeeding tube or receiving device. These parts having the usual A, B and C battery connections as shown.

Extending around the tube 1 from the aerial connection to the plate circuit and the primary coil of the transformer T' I provide an auxiliary or cancelling circuit 9 including a filter 13 which is preferably made with variable parts by which it may be made resonant to any desired frequency. There is also preferably included in this circuit a variable condenser 15 connected to the filter by wire 12 to prevent flow of plate battery through the filter and to regulate the amplitude of the impulse.

In the operation of this circuit the regular receiving device will be tuned to a certain definite frequency which is adapted to be

received by the receiving set. There will be usually included with this frequency certain other disturbing frequencies such as static or other characteristic currents which cannot 5 ordinarily be tuned out by the usual tuning devices and they will pass through the amplifying tube and through the transformer T' at the same time there will be set up in the auxiliary or cancelling circuit 8, 12, 9, frequencies having like characteristics as those 10 in the main circuit except that by reason of the transposition in the transformer they will be in opposite phase or polarity. By bringing the filter 13 into resonance with the 15 main frequency or signal carrying wave intended to be received that particular frequency will be prevented by the filter from passing through the local or auxiliary circuit. There will therefore be impressed 20 upon the receiving circuit in opposite phase or polarity all frequencies, oscillations etc. received by the set, other than the desired frequencies (which will be stopped by the auxiliary or filter circuit) and these being impressed upon the regular receiving circuit 25 will cancel or eliminate all of the disturbing factors leaving only the main signal carrying wave or frequency to pass through the receiving circuit and to the final translating 30 device.

Figs. 3 and 4 are diagrams similar to Fig. 2 with slight modifications in the wiring and connections. In each case the filter 13 is in the auxiliary or cancelling circuit 9, 12 and 35 8. There is however a variable resistance R connected in the circuit and a fixed condenser 15, these being for the purpose of varying the amplitude of the impulses passing through the auxiliary circuit.

40 In Fig. 3 which shows a tube having multiple grids the auxiliary circuit is connected to the auxiliary grid of the tube instead of the regular grid.

Fig. 1 on the same sheet shows the invention applied to a usual form of superheterodyne receiving circuit. In this figure A shows the source of the incoming high frequency oscillations and B represents the source of local oscillations. 1, 2 and 3 represent the tubes of which 1 is the first detector and 2 and 3 the intermediate stages of radio frequency amplification. The wires 6 and 7 lead to the second detector in the usual manner.

55 Two auxiliary circuits with two filters are shown here, one around the detector 1 and the other around the radio amplifying tube 3, the connections and arrangements are substantially the same as shown in Fig. 4.

60 A superheterodyne receiving circuit lends itself readily to the application of my invention from the fact that the radio frequency stages of amplification have at all times a single and fixed frequency to amplify and 65 the filter or filters may be designed and tuned

in a permanent manner, no adjustment of the filter being necessary when different incoming high frequency oscillations or wave lengths are being selected.

Figs. 5 and 6 show further modifications 70 and also show the invention applied to other forms of receiving circuits. In these figures the auxiliary circuit including the filter also has an amplifying tube 10 so that the impulses and oscillations which pass through the auxiliary circuit may be amplified and regulated 75 so that the strength of the cancelling impulses and oscillations will equal in amplitude like impulses and oscillations in the circuit of the receiving set.

In Fig. 5 the transformer T is shown with a double wound and differentially connected primary 5 to which the auxiliary circuit is connected and by means of which the opposite phase or polarity for the impulses passing through the auxiliary circuit and filter are secured.

Fig. 6 shows substantially the same arrangement in which the usual bypass condensers C and C1 are shown in connection with the audio transformer which has the differentially wound primary 5.

Fig. 7 shows a type of wireless receiving circuit especially adapted for the reception of wireless telegraphy or undamped oscillations. In this figure numerals 1 and 2 are radio frequency amplifying tubes shown with transformer coupling. 3 is a detector and wires 6 and 7 lead to the next stage of audio frequency amplification. B shows a local 100 source of oscillations which if desired may include the plate circuit of the detector tube to operate as a self heterodyne. The local circuit is shown connected by wire 9 to the second winding of the radio transformer T 105 and includes the filter 13 with variable resistance R and condenser 14 being so connected that the relative phase angle and amplitude of disturbing impulses and oscillations will cancel and eliminate like and corresponding impulses and oscillations that are 110 present in the grid circuit of tube 1.

Fig. 8 is a somewhat modified circuit in which a radio frequency amplifying tube 10 is used in the auxiliary circuit whose plate circuit is connected to the positive B battery by resistance 15 and wire 18. The filter 13 when properly adjusted will stop the desired tuned in or selected wave length in the receiving circuit and at the same time allow the disturbing influences and oscillations to be impressed upon the grid of the tube 10 by wire 9. These will in turn be amplified in the plate circuit of tube 10 in such manner that their relative phase angle and amplitude will cancel and eliminate like and corresponding impulses and oscillations in the grid circuit of tube 1.

Fig. 9 shows a somewhat similar arrangement with an amplifying radio frequency 130

tube 10 in the local circuit with the filter 13.

Fig. 10 is a detail arrangement of a filtering device which consists of two parallel resonance circuits in series comprising the inductances 13 and 14 respectively connected in parallel with condensers 5 and 6. The wire 8 connects the two units in series. A variable condenser 3 is preferably used to control the amplitude of the oscillations that are permitted to pass through the filter. If desired the condensers 5 and 6 may be on the single shaft for operating the tuning condensers in unison.

Fig. 11 shows another common form of receiving circuit to which the invention is applied. The auxiliary cancelling or filter circuit includes a radio frequency amplifying tube 10 and also a local oscillator 11, the oscillations of which will be modulated by the oscillations or disturbing frequencies which are not stopped by the filter. These modulated oscillations are detected and amplified by the detector 10 and the circuit is connected to the differential winding 5 of the transformer T through the differential winding so that the frequencies of the oscillations will be of the opposite phase or polarity as in the other figures described.

In the construction shown in Fig. 11 in which a local oscillator 11 is used in the cancelling or filtering circuit it is possible under certain conditions to dispense with the filter as the oscillator can be arranged to accomplish the results desired without the necessity of the filter. This would be particularly true in the broadcasting band now in use of from say 200 to 500 meters. The oscillator would be adjusted to a comparatively low radio frequency, or say a frequency of 20,000 cycles and if the incoming or selected frequencies were of the nature of 600,000 cycles or an equivalent wave length of 500 meters, this would have a negligible effect in modulating the frequencies of the oscillator as any one cycle of the 600,000 would have approximately .03 of the 20,000 cycle frequency that it could possibly modulate.

The disturbing frequencies of audio frequency will modulate the oscillations of the oscillator and can be combined with the receiving circuit in the manner before described to eliminate these modulated frequencies from the circuit of the receiving set. This is particularly true also of such disturbances as come from the beat note or heterodyning of two broadcasting stations of different frequencies. With this arrangement the local oscillations modulated by the disturbing oscillations would be impressed upon the receiving circuit and cancel corresponding frequencies and oscillations in the main or receiving circuit.

Fig. 12 shows another conventional form of circuit with two amplifying tubes 10 and 11 in the auxiliary or filter circuit. These

tubes represent a resistance coupled amplifier with tube 11 functioning as a detector. 15 represents a potentiometer which is connected to a C battery 16 in the usual manner. The operation so far as the filter and eliminating function of the circuit are concerned are similar to those already described.

It will be seen from the above description that the invention herein described for eliminating all of the oscillations or disturbing frequencies except the one to be received which is stopped by the filter circuit is readily adapted to various forms of circuits in apparatus now in use.

It will be understood that the various circuit drawings are merely typical and are not intended to show all the various refinements used in present wireless sets, which may be readily applied without in any way interfering with the operation of the filter or cancelling circuit which will permit all undesirable frequencies to pass through the said filtering circuit with an opposite phase or polarity from those in the main receiving circuit and cancel the same while the main or desired frequency to be received is not permitted to pass through the filtering circuit and consequently will be the only one which will pass through the main channel of the receiving set and to the translating device and with the elimination of all disturbing frequencies.

The term "filter" as used in these specifications and claims is meant to describe any circuit such as "parallel resonance", or any combination of inductance, capacity, reactance, or resistance that can be adjusted, or connected so as to oppose, and prevent the passage of a single frequency only, and at the same moment offer a minimum, or zero resistance or reactance to, and permit the passage of currents of all other frequencies. The circuit of the "filter" shown in the various drawings is conventional, and any one of many well known combinations may be used.

Having thus described my invention, I claim:

1. In a wireless receiving set, a filter circuit having means to reject a given frequency and permit other frequencies to pass, said filter circuit being connected at one end to the plate circuit of a vacuum tube in the regular receiving circuit and at the other end to the grid circuit of said tube, means for changing the phase of the frequencies or oscillations passing through the filter circuit and means in the filter circuit for bringing the filter into resonance with any desired frequency which will thereupon be stopped by said filter and impressing the other frequencies in opposite phase upon the regular receiving circuit whereby undesirable frequencies will be cancelled and eliminated.

2. In a wireless receiving circuit having an amplifying tube, an auxiliary circuit in a

shunt around said tube including a filter with means to bring the same into resonance with any desired frequency, the connections to said auxiliary circuit being such that frequencies impressed thereon will be of opposite phase from those in the vacuum tube whereby undesirable oscillations or disturbing frequencies will be cancelled.

- 5 3. In a wireless receiving circuit having a vacuum tube amplifier, an auxiliary filter circuit connected from the plate to the grid side of said tube with means for stopping the passage therethrough of any given frequency with the free passage for other frequencies of opposite phase to those passing through the amplifying tube whereby disturbing influences will be eliminated or cancelled by impressing upon them similar frequencies of like characteristics but of opposite phase.
- 10 4. In a wireless receiving set a thermionic tube, an auxiliary circuit from the plate to the grid of said tube having a variable filter which may be brought into resonance with and prevent the flow of a given frequency while all other frequencies pass uninterruptedly therethrough, means for bringing the frequencies passing through the filter circuit into opposite phase from those passing through the tube, and amplifying devices in said auxiliary filter circuit.
- 15 5. In a system for receiving wireless signals having a termionic tube, an auxiliary circuit from the plate to the grid of said tube with connections such that the frequencies passing through said tube shall be impressed upon the auxiliary circuit in an opposite phase, a local oscillator in said auxiliary circuit of a comparatively low radio frequency which will be modulated by the disturbing impulses within the range of audition and impress these modulations upon the receiving circuit so as to cancel corresponding or like oscillations or impulses in the main circuit.
- 20 6. In a wireless receiving circuit having a vacuum tube, an auxiliary filter circuit connected from the plate to the grid side of said tube, and a transformer with its primary connected to the plate of said tube with its secondary winding included in the auxiliary filter circuit to change the phase of the oscillations passing through said filter circuit to cancel like oscillations in the main receiving circuit.

In testimony whereof, I have hereunto set my hand this 18th day of April, 1928.

WILLIAM M. BRUCE.
